UNITED STATES PATENT OFFICE.

EDGAR D. DICKINSON, OF SCHENECTADY, NEW YORK, ASSIGNOR TO GENERAL ELECTRIC COMPANY, A CORPORATION OF NEW YORK.

VALVE-GEAR.

1,245,576.

Specification of Letters Patent.

Patented Nov. 6, 1917.

Application filed August 30, 1916. Serial No. 117,762.

To all whom it may concern:

Be it known that I, EDGAR D. DICKINSON, a subject of the King of Great Britain, residing at Schenectady, in the county of 5 Schenectady, State of New York, have invented certain new and useful Improvements in Valve-Gears, of which the following is a specification.

The present invention relates to valve 10 gears for controlling the flow of elastic fluid to turbines or other prime movers and has for its primary object to provide an improved structure in valve gears of this general type.

15 A further object of my invention is to provide an improved valve gear which is particularly adapted for installations comprising two turbine elements, as for example, the two turbines or turbine sections which 20 go to make up the forward and reversing elements of a marine installation.

For a consideration of what I believe to be novel and my invention, attention is directed to the accompanying specification and 25 the claims appended thereto.

In the accompanying drawing, Figure 1 is a side elevation of a portion of an elastic fluid turbine with my improved valve gear mounted thereon; Fig. 2 is an end view looking 30 toward the left in Fig. 1; Fig. 3 is a view similar to Fig. 1 but on a smaller scale so as to show the turbine piping arrangement, and Fig. 4 is a perspective view on a larger scale of the valve gear.

35 In the present instance my invention is shown as applied to an elastic fluid turbine comprising a forward section and a reversing section mounted in a common casing, and having a common exhaust, this type of 40 machine being well known in connection with marine propulsion. 5 indicates the turbine casing leading to which is an elastic fluid conduit 6 having two branches 7 and 8, the former of which leads to the forward or 45 "ahead" section of the turbine, and the latter to the reversing or "astern" section. 9 indicates the exhaust conduit which is common to both turbine sections. Arranged in the conduits 7 and 8 are valve mechanisms 50 10 and 11 which control the flow of elastic fluid to the ahead and reverse sections respectively. These two valve mechanisms are preferably alike and may be of any suitable type which is normally biased to closed position. In Fig. 1 the valve mechanism 11 is

shown in section. It comprises a balanced valve having two seats 12 and 13 against which seat the two disks 14 and 15 carried by stem 16. The one end 17 of the stem passes through a stuffing box 18 to the outside of the valve casing and the other end 19 moves in a cylinder 20 to which pressure is admitted by one or more passages 21. By this arrangement it will be seen that the valve is biased toward closed position by

60 the pressure which is exerted on the end 19 of the stem, which will be the pressure of the elastic fluid in the conduit. It will be understood that the valve may be biased to closed position by other means if found de-

65 sirable. Fastened to the end 17 of the stem is a lever 22 pivoted at one end on a link 23 which is supported by a fixed bracket 24. The other end of lever 22 is connected to a

70 link 25 pivoted on the end of an arm 26 fixed to one end of a short shaft 27. The link 25 and arm 26 together form a toggle. The shaft 27 is supported in a bearing 28 carried by the valve casing and on it is fixed 75 an arm 29, on the end of which is pivoted a

rod 30. As will be clear from an inspection of the drawing, a movement of the rod 30 toward the left will rock the shaft 27 in a direction to open the valve mechanism 11, and a movement of it toward the right will 80 rock the shaft 27 in a direction to close it. 85

The valve mechanism 10 is arranged horizontally and at right angles to the valve mechanism 11 and has an actuating mechanism arranged the same as that just de-

90 scribed for valve 11. This actuating mechanism has been omitted from Fig. 1 for the sake of clearness, but it is shown in Figs. 2 and 3, and the same reference numerals

95 with the exponent *a* added have been applied to corresponding parts so far as they show in the drawing. The arrangement is such that the rod 30^a for valve mechanism 10 moves in the opposite direction to rod 30 of valve mechanism 11 in its opening and closing movements.

100 The arrangement for moving the rods 30 and 30^a will now be described. Supported in two bearings 34 is a shaft 35 to one end of which is fixed an operating lever 36 having a handle 37. The shaft 35 is partly broken away in Fig. 2 to show some of the parts behind it. 38 indicates an arm which is fixed on shaft 35 at one end and which is provided at the other end with a

fork 39, which engages trunnions 40 on opposite sides of a short sleeve 41 which slides on the rod 30. The sleeve 41 is adapted to engage an abutment 42 fixed on rod 30 for transmitting motion to it. On the end of rod 30 is an abutment 43 which limits the movement of the sleeve 41 in that direction. 44 indicates an arm, similar to arm 38, which is fixed on shaft 35 and has a forked end 45 which engages trunnions on a short sleeve 46 which slides on rod 30. The sleeve 46 is adapted to engage an abutment 47 on the end of rod 30 for transmitting motion to it. With the above described arrangement when the operating lever 36 is turned to the right (Fig. 1) the sleeve 46 engages abutment 47 thus pulling arm 29 in a direction to open valve mechanism 10 and admit elastic fluid to the ahead section of the turbine. At the same time the sleeve 41 slides on rod 30 with an idle movement, the valve 11 remaining closed. If now the operating lever 36 is turned toward the left, the sleeve 46 is first moved away from abutment 47 thus permitting the valve mechanism 10 to close, it being remembered that such valve mechanism is biased toward closed position. The sleeve 41 on rod 30 then engages abutment 42 and moves the rod 30 so as to turn lever 29 and open the valve mechanism 11, thus admitting elastic fluid to the reversing section of the turbine. It will thus be seen that the one operating lever is used for actuating both valve mechanisms.

It may sometimes happen that the valve mechanisms will stick open, and in order to insure their being positively closed under such circumstances the following arrangement is provided. Each of the forks 39 and 45 is provided with a hook 48 pivoted at 49. The end 50 of the hook has a slot in it through which the bolt 51 passes and it is held in fixed position in the slot by two bolts 52. By moving the two bolts 52 the hook can be adjusted on its pivot 49. On each of stops 42 and 47 is a pin 53. When the valve mechanisms are closed the hooks 48 are disengaged from the pins 53, but when either valve mechanism is opened the corresponding hook moves around the pin and into a position to engage it on the closing movement of the operating lever should the valve mechanism stick open. Referring to Fig. 1 it will be seen that the tip of the hook 48 is just below pin 53. If the operating lever 36 is moved to the left, the hook will pass under the pin, the adjustment of it being such as to just provide for this. On the other hand, if the operating lever 36 is moved to the right to open valve mechanism 11, then the hook 48 will move up around pin 53, and if on the closing operation the abutment 42 fails to follow the movement of the sleeve 41, due, for example,

to the sticking open of the valve mechanism, then the hook will come into engagement with the pin and positively close the valve mechanism.

55 indicates a segment over which the operating lever 36 moves and to which it may be clamped in any adjusted position. The clamping means comprises a short arm 56 pivoted on the lever 36 with its end behind the segment 55. 57 indicates a bolt which passes through the arm 56 and lever 36 and has a wing nut on its free end. By screwing this wing nut up, the lever 36 is clamped to the segment 55. The segment 55 is pivoted on shaft 35 and is held from turning by a latch 60 engaging a notch 61 in it. The latch 60 is fixed on a shaft 62 journaled in bearings 63 and is held in the notch 61 by a suitable spring 64. On shaft 62 is fixed an arm 65 to the end of which is fastened a rod 66 connected to a lever 67 which forms a part of an emergency governor mechanism. The lever 67 is pivoted on a bracket 68 and to it is connected a rod 69 which extends down to a point adjacent the turbine shaft. The details of the governor mechanism are not shown as it forms no part of the present invention. It will be understood that it comprises any suitable arrangement which, when the speed of the turbine reaches a predetermined high value, operates on the rod 69 to cause it to be lowered, thus rocking the shaft 62 and disengaging the latch 60 from notch 61. As will be clear when this occurs the segment 55 is released, thus releasing the lever arm 36 which will be returned to neutral position, carrying with it the segment 55 to which it is clamped. This movement to neutral position occurs because the valve mechanisms 10 and 11 are both biased to closed position. 70 indicates a resetting handle for the emergency governor mechanism and 71 stops at the two lower outer corners of the segment 55 to limit the movement of the operating lever 36. 72 is a hand valve in the conduit 8 which may be closed manually to cut off the flow of elastic fluid to the reversing section of the turbine.

From the foregoing description it is believed that the operation of my improved apparatus will be clear without further explanation.

The structure has the advantages that it is simple and compact and that only a single operating lever is required for both valve mechanisms. Also it has the advantages that a single emergency speed governor mechanism operates to cause the closing of either valve mechanism in case of excess speed, and that in case one of the valves should tend to stick open, it will be positively closed.

In accordance with the provisions of the patent statutes, I have described the prin-

5 ciple of operation of my invention, together with the apparatus which I now consider to represent the best embodiment thereof; but I desire to have it understood that the apparatus shown is only illustrative, and that the invention can be carried out by any other means.

What I claim as new and desire to secure by Letters Patent of the United States, is:—

- 10 1. In an apparatus of the character described, the combination of two turbine elements, a conduit for conveying elastic fluid to each, a valve mechanism in each conduit, means biasing them to closed positions, a single controlling device for said valve mechanisms which when operated in one direction opens one of the valves and when operated in another direction opens the other, said controlling device permitting the one 15 valve mechanism to close prior to the opening of the other, a pivotally supported segment over which said controlling device moves, means for clamping the controlling device to the segment in any adjusted position, a latch for holding the segment to prevent it from moving on its support, and means for releasing said latch whereby either of said valve mechanisms may quickly move to closed position.
- 20 2. In an apparatus of the character described, the combination of a forward turbine element, a reversing turbine element, a conduit for conveying elastic fluid to each, a valve mechanism in each conduit, means biasing them to closed positions, an operating lever common to the two valve mechanisms which when moved in one direction opens one of them and when moved in another direction opens the other, said operating lever permitting the one valve mechanism to close prior to the opening of the other, a pivotally supported segment over which said operating lever moves, a latch for holding it in fixed position relative to 25 its support, means controlled by the speed of the turbine for releasing said latch, and

means for clamping the operating lever to the segment.

3. In an apparatus of the character described, the combination of a forward turbine element, a reversing turbine element, a conduit for conveying elastic fluid to each, a valve mechanism in each conduit, means biasing them to closed positions, an operating lever common to the two valve mechanisms which when moved in one direction opens one of them and when moved in another direction opens the other, a shaft upon which said operating lever is fixed, means connecting the shaft to the valve mechanisms, a segment pivoted on said shaft and over which the operating lever moves, means for clamping the operating lever to the segment, a latch for holding the segment from turning and means for releasing the latch in case of excess speed of the turbine.

4. In an apparatus of the character described, the combination of two turbine elements, a conduit for conveying elastic fluid to each, a valve mechanism in each conduit, means biasing them to closed positions, an operating rod for each valve mechanism, a shaft, a lost motion connection between each rod and the shaft, said shaft when turned in one direction opening one of said valve mechanisms and when turned in the other direction opening the other and permitting the one to close if open, an operating member for the shaft, a pivoted segment over which it moves, means for clamping the member to the segment, a latch which engages the segment to hold it in fixed position, and means for releasing the latch whereby either of said valve mechanisms may quickly move to closed position.

In witness whereof, I have hereunto set my hand this 26th day of August, 1916.

EDGAR D. DICKINSON.
